United States Patent

Des. 240,353
Patented June 29, 1976

240,353

COMPARTMENTED FOOD CONTAINER

Richard Thomas Edwards, 13 Howard Drive,
Middletown, N.Y. 10940

Filed Feb. 26, 1974, Ser. No. 445,944

Term of patent 14 years

Int. Cl. D9—03

U.S. Cl. D9—183

FIG. 1

FIG. 2

FIG. 3

FIG. 4

FIG. 5

FIG. 1 is a top perspective view of a compartmented food container showing my new design;

FIG. 2 is a perspective view on a smaller scale with the cover in open position;

FIG. 3 is a rear elevational view with the cover closed;

FIG. 4 is a top plan view on the same scale as FIG. 1 with the cover fully opened; and

FIG. 5 is a vertical sectional view taken on the line 5-5 of FIG. 4.

I claim:

The ornamental design for a compartmented food container, as shown.
